GAS INSTALLATION HOUSING

Peter A. Anderson, Portland, Maine

Application May 25, 1937, Serial No. 144,757

3 Claims. (Cl. 312—112)

The present invention relates to improvements in gas installation housing and has for an object to provide an improved housing particularly for liquefied petroleum gas installation in which a back plate constitutes the support both for the regulating equipment and for a hood which is hinged to the back plate and may be swung upwardly to give better access to such regulator.

The invention also contemplates the use, in connection with such back plate and hood of an arm for supporting the hood prop.

A further object of the invention is to provide an improved back plate and hood in which both parts cooperate with pipe standings, or without pipe standings.

A still further object of the invention is to produce a one-piece hood, a back plate which also combines to form a hinge for the hood, and a structure which eliminates doors, is more durable than existing structures, is streamlined in design and economical to manufacture.

A still further object of the invention is to the production of a housing for a two-drum installation, in which not only the bottles, but also the regulators and pigtails are completely covered.

A still further object of the invention is to provide a housing for a two-drum installation accommodating any size drum and usable on practically any type of commercial installation.

With the foregoing and other objects in view the invention will be more fully described herein-after and more particularly pointed out in the appended claims.

In the drawings in which like reference characters denote like or corresponding parts throughout the several views,

Figure 1 is a front elevation, with parts broken away and parts shown in section of an installation with the improved housing shown in the closed position.

Figure 2 is a top plan view of the same with parts broken away and parts shown in section.

Figure 3 is a side elevation with the support and hood shown in section and with the hood in the elevated position.

Figure 4 is a perspective view of the improved back plate and hinge.

Figure 5 is a similar view of the prop support and combination lock arm.

Figure 6 is a perspective view of the rod or prop, and

Figure 7 is a front view, with parts broken away and parts shown in section, and illustrating an optional form of pipe standard.

Referring more particularly to the drawings 18 designates a brick or stone wall, a wooden wall, or other appropriate support to which the back plate 11 is affixed by the use of nails, screws, bolts or other fastenings 12, or in case of stone or brick

wall pipe standard may be used in place of nails, screws, etc.

As best seen in Figures 3 and 4, the major portion of the back plate is offset forwardly from the support 10. At or near its lower end this back plate is provided with a spacing shoulder 13 and a foot 14 having the holes or perforations 15 to receive the fastenings 12 by which the lower part of the plate is secured to the wall 10.

At its upper portion the back plate 11 is provided with a spacing shoulder 16 associated with an elongated flange or head strip 17. The upper end of this head strip is rolled, as at 18 to mesh with the rolled leaves 19 of a hinge plate 20. A hinge pintle 21 passes through the rolled portion 15 and unites the plate 20 to the head strip 17, whereby the hinge member 20 is carried and supported by the back plate 11.

The hinge plate has openings 22 for fastenings 23, for instance rivets by which the hinge plate 20 is secured to the upper side of a protecting hood. This hood is formed by substantially semi-circular upper wall 24 and a front wall 25. The inner end of the hood is open. Likewise the bottom of such hood is open.

The back plate 11 is formed with appropriate openings 26 and 28 to receive fastenings for supporting the regulators or the regulating equipment 27, it being understood that the form of regulator shown in the drawings is merely for purposes of illustration and that the improved housing may be used in connection with any type of regulating equipment. The back plate 11 will thus hold the regulating equipment with reference to the hood whereby the hood may completely cover, house and protect the same.

A bracket is fastened to the back side of plate 11, by welding or other fastening processes such as rivets 29, screws etc. It is for the purpose of supporting the prop by which the hood is held in place when open, also for the purpose of locking hood.

This bracket is more particularly illustrated in Figure 5 and is composed generally of the arms 32 and 33 connected angularly by the elbow 34. The arm 33 carries at its forward end the diagonal arm 35, and on the outer end of such diagonal arm is the terminal flange 36 having two or more openings 37. The arm 32, as best seen in Figure 2, lies along the face of the support 10. The arm 33 extends out from the wall or back plate at substantially right angles or perpendicularly thereto at the side of regulating equipment 27. The purpose of the arms 32 and 33 is to secure support from the back plate for the bracket but at the same time to avoid the regulating equipment.

The diagonal arm 35 is for the purpose of bringing the flange 36 out substantially centrally of the hood and centrally of the back plate with-

out interference from the regulating equipment. It is desirable to have the flange 36 in a central position with respect to the hood in order that the rod or prop 38, shown in Figures 3 and 6, may engage the hood in alignment with the hinge and in alignment with its center mass to better support the same; also that flange 36 may protrude through slot 43, best illustrated in Figure 3, so that padlock may be placed in outer opening 37 for the purpose of locking the equipment when not servicing, inspecting or otherwise manipulating. The prop 38 is formed at one end with the offset pin 39 and connecting shoulder 40. At the other end it is similarly formed with the shoulder 41 and the offset pin 42.

The hood in its front wall 25 near the lower edge thereof is formed with one or more openings or perforations 43.

In the use of the device, the back plate 11 is attached to the wall 10 by the use of fastenings 12 of appropriate character or pipe legs 45. The regulating equipment 21 is mounted upon the back plate 11. The hood may be attached to the hinge plate 20 before the back plate is mounted in place or afterwards. When the hood is mounted the rear edge of its upper wall 24 engages against the support 10 and the lower edge of the wall 24 extends down a sufficient distance to house and protect the regulating equipment. When access to the regulating equipment is to be had the hood may be raised, for instance to the position shown in Figure 3, and if desired held in this raised position by the prop or support 38 leaving the workman's hands free to adjust, to repair, to attach or detach or to replace the regulating equipment or other parts. The pin 39 of the prop 38 is insertable in inner hole 37 of the flange 36. When so inserted the rod 38 is turned so that the shoulder 40 will move into the engaged opening, in which case the pin 39, being angularly disposed with reference to the shoulder 40, will act at one side of the flange 36 to retain the prop or rod 38 upon the bracket. The rod 38 itself will engage the opposite wall 45 of the flange 36 to prevent the shoulder 40 from going through the engaged perforation in this direction. The shoulder 40, partaking of the cross section of the rod 38, is rounded or substantially so, and therefore the prop or rod may rotate freely about the flange 36.

The upper pin 42 of the prop 38, while fitting sufficiently loosely in the aperture 43 of the hood so that no great care need be taken in fitting this pin 42 to the aperture, nevertheless the aperture 55 43 is not of such great diameter that the shoulder 41 would pass therethrough. The shoulder 41 constitutes a stop or a rest against which that portion of the wall 25 of the hood immediately surrounding the aperture 43 engages. Thus the 60 rod 38 supports the hood 25 as shown in Figure 3. By lifting the hood, as by engaging the lower edge of its front wall 25 in the hand and lifting the same, the aperture 43 will be removed from the pin 42, and the rod or prop 38 may be allowed to descend by rotation about the bracket 65 flange 36 until such rod 38 hangs down by gravity, or may be placed in a broadly speaking upright position resting against the wall under the hood. It may be left in this place or it may be 70 removed by turning the rod and withdrawing the pin 39 axially from the opening 37.

In Figure 3 the hood is shown as having cut-

out portions 44 to receive and accommodate rods 45 shown in Figure 7. These cut-out and bent-over portions also serve the purpose of holding the equipment more rigid. The rods extend down and telescope with other rods 46, the rods being held in place by set-screws 47. The upper convergent ends of the rod 45 may be affixed to the back plate as by fastenings 48 entering openings 26 of the back plate 11.

The back plate 11 forms at once a support for the hood and for the regulating equipment. It also forms the support for the bracket, the bracket being so formed as to derive its support and centering from the back plate and to engage by means of the prop centrally with the hood without interference from the regulating equipment.

The hood may be a one-piece seamless metallic structure which will be of light weight yet strong and durable and of economical manufacture.

It is obvious that various changes and modifications may be made in the details of construction and design of the above specifically described embodiment of this invention without departing from the spirit thereof, such changes and modifications being restricted only by the scope of the following claims:—

1. In a housing installation, a back plate having means to support the same from a support, a hood hinged to said back plate to open upwardly, a bracket composed of angularly joined arms with a diagonal arm extending forwardly therefrom and a perforated terminal flange on the diagonal arm, said bracket mounted on the back plate, a prop releasably and rotatably carried by said flange and formed with a cooperating pin and shoulder, said hood having an opening to releasably engage said pin with an adjoining wall whereby the hood may rest upon said shoulder. 30 35 40

2. In a housing installation, a back plate having means to secure the same to a support, a hood hinged at its upper rear portion to an upper part of said plate whereby the hood may open upwardly about the hinge connection, a bracket composed of angularly joined arms with a diagonal arm extending forwardly therefrom and a perforated terminal flange on the diagonal arm, one of the angular arms being fixed to said back plate, and a prop releasably and rotatably carried by said flange and formed with a cooperating pin and shoulder, said hood having an opening at its forward lower portion to releasably engage said pin with an adjoining wall whereby the hood may rest upon said shoulder when the hood is raised. 55

3. In a housing installation, a hood, means for hingedly mounting the hood upon a support with the hood opening upwardly, said hood having at its forward lower portion an opening with a wall adjoining the opening, a bracket supported by said means within the lower portion of the hood and having an outer portion for receiving a padlock, said outer portion positioned to project through said opening when the hood is in the lowered position, and a prop rotatably carried by the outer portion of said bracket and having a pin on its upper end for fitting in the opening of the hood when raised and a shoulder to support said adjoining wall. 60 65 70 75 80 85 90 95 100
